DENTAL MODEL TRIMMING HOUSING

Velton C. White, 17 N. Broadway,
Des Plaines, Ill. 60016

Filed Jan. 12, 1973, Ser. No. 323,285

Term of patent 14 years

Int. Cl. D15—09; D24—02

U.S. Cl. D37—1 A

FIG. 1 is a perspective view of a dental model trimming housing showing my new design;

FIG. 2 is a side elevational view of the housing;

FIG. 3 is a front elevational view of the housing;

FIG. 4 is a rear elevational view of the housing;

FIG. 5 is a top plan view of the housing; and

FIG. 6 is a bottom plan view of the housing.

I claim:

The ornamental design for a dental model trimming housing, as shown.
